His Attorney.

UNITED STATES PATENT OFFICE

2,128,862

VAPOR ELECTRIC DISCHARGE DEVICE

Lewi Tonks, Schenectady, N. Y., assignor to General Electric Company, a corporation of New York

Application July 16, 1936, Serial No. 90,868

8 Claims. (Cl. 175—354)

The present invention relates to vapor electric discharge devices, and more particularly to improved means for controlling the operation of such devices.

5 In my copending application, Serial No. 90,867, filed July 13, 1936, and also assigned to the General Electric Company, I have described and claimed an improved means for anchoring the cathode spot of a pool-type discharge device on a 10 rigid relatively invariable surface.

It is an object of the present invention to provide in connection with such a spot-anchoring device means whereby the properties of the device may be advantageously utilized in controlling 15 the initiation of an arc discharge.

A further object of the invention consists in the combination with a pool-type discharge device having a cathode spot-anchoring means of an excitation circuit which is operable intermittently to effect instantaneous control of the 20 device.

The features of novelty which I desire to protect herein are pointed out with particularity in the appended claims. The invention itself, however, both with respect to its construction and mode of operation, together with further objects and advantages thereof, will best be understood by reference to the following specification taken in connection with the drawing, in which Figs. 30 1 and 2 show in front and side elevation respectively a particular mode of application of the invention, and Fig. 3 shows a preferred circuit arrangement suitable for the effective utilization of the discharge device of Fig. 1.

35 Referring particularly to Figs. 1 and 2 I have illustrated a discharge device in which a cathode spot-anchoring means may be advantageously used in connection with means for controlling the initiation of a discharge. As shown, this device 40 comprises an envelope 1 containing an anode 2, for example of steel, a mercury pool cathode 3 and a spot-anchor 4. The anchor 4 is preferably constituted of the material described in my aforementioned application, Serial No. 90,867.

45 The material therein described comprises carbonized cohering particles of a metal of the group consisting of tantalum, tungsten and molybdenum, such particles being so combined as to produce a porous wick-like structure. These materials may be wet with mercury in various ways, for example by heating to an elevated temperature and plunging below the mercury surface in the presence of hydrogen, or of an inert atmosphere. After once being completely immersed 50 and impregnated with mercury, they have the

property of retaining their wetness under varying conditions and will resist disintegration even after a considerable period of use in a discharge device. As a result of the porosity of the anchoring body and of its ability to be wet by 5 mercury, it acts as a wick and develops sufficient capillarity to draw mercury from the cathode pool 3 to its upper exposed surface which thus retains a thin film of mercury during the operation of the device. This mercury is effectively 10 immobilized in the sense of being unable to vary in level or position after the manner of the main cathode surface. Arranged in fixed relation to the upper surface of the anchor 4 I provide a 15 sparking electrode 6 comprising, in this instance, a tapered strip of refractory conducting material, for example, molybdenum having one edge thereof directed toward the upper surface of the anchor. The various electrodes are furnished with suitable lead-in conductors 8, 9 and 10, respectively, for impressing desired potentials thereon.

The mode of utilization of a tube of this construction may be understood by reference to Fig. 3 in which I have illustrated a regulating circuit 25 adapted to modify the characteristics of an alternating potential supplied from an input source 16 to a load which is to be connected at 17. Regulation is accomplished by means of two discharge devices 1 and 1' corresponding to the device described in connection with Fig. 1. These are 30 connected in a manner well understood in the art, so that one is adapted to conduct during positive half cycles, while the other is capable of conducting during negative half cycles. By means more fully described in the following, each 35 device may be controlled so that it is conductive during only a desired portion of a half cycle rather than a full half cycle. In this way the amount of power transmitted can be regulated within close limits.

40 The control system for the two discharge devices is supplied with potential from the secondary of a phase-shifting transformer 19 of known construction, which potential is impressed between the various sparking electrodes and the 45 corresponding anchoring bodies by means of a suitable step-up transformer 20. Referring particularly to the circuit associated with the discharge device 1, the phase angle of the transformer 19 is so adjusted that the plates of the 50 condenser C connected to the sparking electrode 6 are cyclically charged through the resistor 23 in desired relation to the cyclical variations in the potential impressed between the anode and the cathode of the device. The adjustment is 55

such that the condenser potential attains a value sufficient to produce a sparking discharge through the resistor R and from the electrode 6 to the anchor 4 at a desired moment during the period 5 when the anode 2 is positive with respect to the cathode 3 . I have found it to be highly desirable for consistent operation that the sparking discharge be non-oscillatory and comprise a unidirectional pulse of current proceeding in the 10 positive sense from the sparking electrode to the anchor body. This condition will be sufficiently fulfilled in the circuit of Fig. 3 when the resistance of 23 is roughly at least ten times the resistance of R and when the quantity $4L/R^2C$ is 15 less than about 4 where L is the self-inductance of the sparking circuit in henries and R and C are the values of the resistance R in ohms and of the capacity of condenser C in farads respectively. Otherwise expressed, the inductance of the 20 circuit should be less than the product of the capacitance of the condenser C and the square of the resistance of the resistor R . It is also desirable for consistent operation that the peak current in the spark exceed approximately one-half ampere and that the quantities L , C and R should be so proportioned with respect to the breakdown voltage of the spark gap that this condition is attained.

It will be understood that the sparking circuit 30 associated with the discharge device $1'$ is identical with that just described, except that the sparking discharge is timed to occur substantially 180° out-of-phase with that of the discharge device 1 . In both these circuits, although the charging of 35 the condenser C has been described as being accomplished through the resistor 23 , other current limiting devices such, for example, as a thermionic tube of controllable unidirectional conductivity may be used for this purpose.

40 In the foregoing I have referred to mercury as an exemplary cathode material. It should be understood, however, that other liquid metals, for example, gallium, or sodium or cadmium when in the liquid phase may alternatively be employed.

45 Furthermore, while I have shown particular structural embodiments of my invention, it will be understood that many modifications may be made by those skilled in the art without departing from the invention, and I aim by the appended 50 claims to cover all such modifications as fall within the true spirit and scope of the invention.

What I claim as new and desire to secure by Letters Patent of the United States is:

1. In an electrical discharge device, an anode, 55 a rigid body having a surface adapted to substantially immobilize a quantity of mercury thereon, means for supplying mercury to said surface, a sparking electrode in fixed spaced relation to said surface, means for impressing a difference of potential between said anode and said body, an energizing circuit for producing a spark discharge between said electrode and said surface, and means associated with said circuit for causing such discharge to be non-oscillatory.

65 2. In an electrical discharge device, an anode, a rigid body having a surface adapted substantially to immobilize a quantity of mercury thereon, means supplying mercury to said surface, a sparking electrode in fixed spaced relation to 70 said surface, means for impressing a cyclically varying discharge potential between said anode and said body, means including an energy source for cyclically creating a spark discharge from said electrode to said surface, said last-named means 75 being operable in predetermined relation to the

variations of said discharge potential and means in circuit with said energy source for causing said discharge to be of a non-oscillatory character.

3. In an electrical discharge device, an anode, a rigid body having a surface adapted to retain a quantity of mercury thereon, means for supplying mercury to said surface, a sparking electrode in fixed relation to said surface, means for impressing a difference of potential between said anode and said body, means for creating a discharge between said electrode and said surface, said means comprising a condenser, a circuit including a resistor for impressing the voltage of said condenser between said electrode and said surface, and means for charging said condenser, 15 said condenser and said resistor being so proportioned with respect to the inductance of said circuit as to cause said discharge to be non-oscillatory.

4. In an electrical discharge device, an anode, 20 a cathode comprising a rigid body having a surface adapted to retain a quantity of mercury thereon, and means for supplying mercury to said surface, a sparking electrode in fixed relation to said surface, means for impressing a 25 difference of potential between said anode and said cathode, means for creating a discharge between said electrode and said surface, said means comprising a condenser, a circuit including a resistor for impressing the voltage of said 30 condenser between said electrode and said surface, and means for charging said condenser, the inductance of said circuit being less than the product of the capacitance of said condenser and the square of the resistance of said resistor. 35

5. In an electrical discharge device, an anode, a mercury pool cathode including a cathode spot-fixing body, a sparking electrode in fixed relation to said body, means for impressing a difference of potential between said anode and said cathode, 40 and means for creating a non-oscillatory discharge between said electrode and said body which discharge has a current intensity in excess of about 0.5 amperes.

6. In combination, an anode, a cathode including a pool of liquid cathode material and a rigid body having a switch-like discharge-receiving surface which is adapted to retain a thin film of liquid cathode material thereon, said surface being appreciably above the normal level 50 of the pool, means supplying cathode material to said surface to maintain said film, a sparking electrode positioned at a fixed sparking distance from said surface, means for energizing said anode and cathode, and means including said 55 sparking electrode for controlling in a desired manner the initiation of a discharge between the anode and cathode upon the application of a favorable potential between them, said last named means comprising an energizing circuit 60 operable intermittently in response to a controlling influence to create a spark discharge between said electrode and said body.

7. In combination, an anode, a cathode including a pool of liquid cathode material, a porous 65 wick-like body in contact with the cathode material and having an exposed surface appreciably above the normal level of the pool, said body acting by capillarity to maintain a film of cathode material on said surface, a sparking electrode 70 disposed at a fixed distance from said surface, means for energizing said anode and cathode, and means including said sparking electrode for controlling in a desired manner the initiation of discharge between the anode and cathode upon 75

the application of a favorable potential between them, said last named means comprising an energizing circuit operable intermittently in response to a controlling influence to create a spark discharge between said electrode and said body.

8. In combination, an anode, a cathode including a pool of liquid cathode material, a porous wick-like body in contact with the cathode material and having an exposed surface appreciably above the normal level of the pool, said body acting by capillarity to maintain a film of cathode

material on said surface, a sparking electrode disposed at a fixed distance from said surface, means for impressing a cyclically varying discharge potential between the main anode and cathode, and means for cyclically creating a spark discharge between said sparking electrode and said body, said last named means being operable in predetermined relation to the cyclical variations of said discharge potential.
